UNITED STATES PATENT OFFICE.

HIRAM MOE SHAW, OF GENOA, NEW YORK.

POTATO-DIGGER.

SPECIFICATION forming part of Letters Patent No. 398,545, dated February 26, 1889.

Application filed December 10, 1887. Serial No. 257,489. (No model.)

To all whom it may concern:

Be it known that I, HIRAM MOE SHAW, of Genoa, in the county of Cayuga and State of New York, have invented a new and Improved Potato-Digger, of which the following is a full, clear, and exact description.

My invention relates to a machine intended for digging potatoes, and has for its object to provide a simple, inexpensive, and efficient machine of this character which will dig the potatoes and then separate them from the earth so that they may be readily gathered for market.

The invention consists in certain novel features of construction and combinations of parts of the potato-digger, all as hereinafter described and claimed.

Reference is to be had to the accompanying drawings, forming a part of this specification, in which similar letters of reference indicate corresponding parts in all the figures.

Figure 1 is a plan view of my improved potato-digger with one of the sulky-wheels and part of the separator-driving gearing in horizontal section. Fig. 2 is a side view of the machine with parts in section on the line *x x*, Fig. 1; and Fig. 3 is a rear detail view of the separator-driving gearing and adjacent parts.

The machine is made with a sulky comprising an axle, A, two wheels, B B, thereon, a tongue or pole C, and draft-trees D on the tongue. The frame of the potato-digging mechanism consists of a couple of beams or bars, E F, which are held to opposite end parts of the axle A, and preferably by a pivotal connection, allowing the bars to be raised or lowered by means of handles G G, connected to them, and which will be grasped by an operator walking behind the machine.

The handles are connected by a cross-bar, g.

The digging blade or hoe H extends across the rear end of the machine, and is fixed at opposite ends to the lower forwardly-curved ends of the beams or bars E F. The blade lies flat, or nearly so, and is formed with a central forwardly-projecting point, h, which cuts into the center of the hills of potatoes as the machine moves forward, and the straight portions of the blade, at either side of the point h, complete the digging operation. The dug potatoes, with the dislodged earth, pass back-

ward over the blade onto an agitator, which separates the potatoes and earth, as presently described. This agitator consists of a bar, I, which is pivoted at opposite ends in the hoe-beams E F and ranges along immediately behind the hoe-blade H, and is provided with a series of backwardly-extending fingers or tines, J, the agitator thus having the general form of a fork. To the bar I, near one end of it, is connected a pin or arm, K, to which is attached the lower end of a pitman, L, the upper end of which connects with a wrist-pin, M, set eccentrically in a disk-wheel, N, which is fixed to a shaft, O, journaled in the laterally-bent portion e of the hoe-beam E and in an arm, e', connected to the beam. The forward end of the shaft O carries a bevel-pinion, P, which meshes with a bevel gear-wheel, R, fixed to the inner face of the adjacent sulky-wheel B.

It is obvious that as the machine moves forward the fork I J will be oscillated vertically by the last above-described mechanism driven from the sulky-wheel, and the potatoes and earth dislodged by the hoe H and passed therefrom onto the fork will be thoroughly agitated thereby to separate the potatoes from the earth and leave them on the field in a condition to be readily picked up or gathered for market.

The operation of this machine is very simple and effective, and there is nothing about its construction which is liable to easily get out of order, and it may be successfully worked by any ordinary farm-hand.

Having thus described my invention, what I claim as new, and desire to secure by Letters Patent, is—

1. In a potato-digger, the combination, with the axle A, wheels B, and gear-wheel R on one of its wheels B, of beams E, pivoted on the axle, a blade, H, secured to and connecting the beams, a shaft, I, journaled in the beams in rear of the blade and provided with tines J and the arm K, the shaft O, journaled in the beams E and provided with the gear-wheel P, meshing with the gear-wheel on the drive-wheel, and with a wrist-pin, M, at its other end, and the pitman L, connected to the arm K and to the wrist-pin M, substantially as herein shown and described.

2. In a potato-digger, the combination, with the axle A, the wheels B, and gear-wheel R on one of the wheels, of the beams E F, pivoted to axle, the handles G, secured to the beams, the 5 narrow blade H, secured to the beams and having the central forwardly-projecting point, h, the shaft I, journaled in the beams in rear of the blade and provided with the tines J and

the arm K, the shaft O, journaled in the beam E and provided with the gear-wheel P and the 10 crank-pin M, and the pitman L, substantially as herein shown and described.

HIRAM MOE SHIAW.
